UNITED STATES PATENT OFFICE.

CORRY B. COMSTOCK, OF NEW YORK, N. Y.

PLASTER-KEY.

1,085,021.

Specification of Letters Patent.

Patented Jan. 20, 1914.

Application filed June 26, 1911. Serial No. 635,346.

To all whom it may concern:

Be it known that I, CORRY B. COMSTOCK, a citizen of the United States, residing at New York, in the county of New York and State of New York, have invented certain new and useful Improvements in Plaster-Keys, of which the following is a specification, reference being had therein to the accompanying drawing.

This invention relates to devices for interlocking layers of materials such as concrete and plaster.

While the primary object of the invention is to provide keys which may be embedded in a concrete wall or ceiling and thereby provide recesses within which plaster or other facing material may be pressed to securely hold it in contact with the concrete, it may also be used in other ways for joining two plastic substances.

Referring to the drawings: Figure 1 is a side elevation. Fig. 2 shows two vertical transverse sections, one on the line *a—a* and the other on the line *b—b* of Fig. 1. Fig. 3 is an end elevation. Fig. 4 is an inverted plan view. Fig. 5 is a cross section taken through a concrete floor, on the under side of which plaster has been attached by means of the device. Fig. 6 is a plan view showing several of the elements placed upon the inner surface of a mold ready to receive the concrete. Fig. 7 is a perspective view of an end of the device in a modified form.

In the drawings, the numeral 1 indicates, in general, a long tube-like piece of metal or other suitable material having an approximately three-quarter circular cross section with a longitudinal slot 2. The material is formed outward from the edges 3 of the opening 2 into wings or flanges 4. These flanges are in substantially the same plane and are perpendicular to a plane passed through the center of the opening 2 and diametrically through the tubular circular portion 1.

An economical way to manufacture this plaster key, as it may be termed, is to form long strips with this approximately three-quarter circular winged cross section and shear off pieces of a desired length. The shearing process will close the ends of the tubular strips and give it substantially the form shown in Fig. 3. The flanges are of sufficient area to form a stable base portion and will maintain the pieces in an upright position with the opening downward.

Fig. 7 illustrates a modification in which a corner of the flange is bent downward at right angles forming a point 5 which may be driven into a wooden mold and thereby retaining the key in any position in which it is placed. This facilitates placing the keys upon an inner surface of a vertical mold such as is used in forming a wall and prevents their displacement when the concrete is forced into the mold.

Figs. 5 and 6 illustrate the manner in which the keys are used in securing the plaster to a concrete wall or ceiling. The keys are first placed upon the mold with the flanges contacting with the surface of the mold which will later be replaced by plaster or other covering material. The concrete is then run in and tamped and after a suitable time has elapsed the wooden mold is torn away. The result is that the surface now presents a multiplicity of slots or openings into which the plaster will be forced and consequently key it in place and thereby be prevented from displacement. The ends of the keys are closed in the shearing process so as to prevent concrete from running in at the ends and occupying space which the plaster is later to fill.

What I claim is:

1. A key for securing one layer of plastic material to another consisting of an isolated short tubular section having a slot of a width less than the width of the tubular section and extending from end to end thereof and wings extending outward from the edges of the slot and in the same plane.

2. A key for securing one layer of plastic material to another consisting of a short tubular section provided with a slot of a width less than the width of the tubular section and extending from end to end thereof, the said section having its walls pinched together at each end forming a chamber.

3. A key for securing one layer of plastic material to another consisting of an isolated short tubular section provided with a slot of a width less than the width of the tubular section and extending from end to end thereof, wings extending outward from the edges of the slot and in the same plane, the said section having its walls pinched together at each end, thereby forming a chamber.

4. A device of the class described consisting of a tubular element provided with a longitudinal opening and closed at its ends, flanges formed outward from the edges of

the opening, and pointed projections formed from said wings at approximately 90° thereto.

5. A device of the class described consisting of a strip of material so formed that it has an approximate three-quarter circular cross section with the edges of the circular portion extended outward to form wings located in substantially the same plane, and 10 pointed projections formed from said wings downward at approximately 90° thereto.

6. A device of the class described consisting of a tubular element closed at its ends and provided with a longitudinal opening, 15 the longitudinal edges bent outward to form wings located in a plane approximately perpendicular to a plane passed through the

center of the opening and diametrical to the tubular portion, and pointed projections extending downward from said wings at approximately 90°. 20

7. A device of the class described consisting of a hollow element provided with a longitudinal opening, the edges formed by said opening formed outward into wings located 25 in substantially the same plane, and projections formed downward from said wings.

In testimony whereof I affix my signature, in presence of two witnesses.

CORRY B. COMSTOCK.
